UNITED STATES PATENT OFFICE.

EDWARD COUSENS, OF CHISWICK, LONDON, ENGLAND.

FILTER.

1,120,448.

Specification of Letters Patent.

Patented Dec. 8, 1914.

Application filed February 21, 1914. Serial No. 820,177.

To all whom it may concern:

Be it known that I, EDWARD COUSENS, a subject of the King of Great Britain and Ireland, residing at "Ilchester," Chiswick, London, W., England, have invented new and useful Improvements in Filters, of which the following is a specification.

This invention relates to apparatus by means of which water or mineral water and liquids generally can be rendered radioactive and micro-organisms contained in said waters and liquids be destroyed by the rays and emanations given off by the radioactive material contained in the apparatus.

15 The main object of the invention is to construct an apparatus fulfilling the above referred to purpose in such manner that the block containing the radioactive material will be supported at such a level below the outlet of the apparatus that said block will be always submerged, so that there will be no waste of rays and emanations such as necessarily occur when the block is exposed to the air.

20 A further object of the invention is to construct an apparatus for the purposes of the invention in such manner that the receptacle for the water or liquid to be rendered radioactive, the support for the block containing the radioactive material and the passage by which said support is placed in communication with said receptacle will form a structural entity which can be readily removed from the containing vessel by the mere act of lifting, thus facilitating the cleaning of the apparatus and the replacement of said block.

25 The invention is illustrated by the accompanying drawings.

30 Of these drawings Figure 1 is a vertical section of one form of apparatus, and Fig. 2 is a sectional plan thereof, the section being taken on the line *a—a* of Fig. 1. Fig. 3 is a vertical section of a slightly modified construction of apparatus, and Fig. 4 is a plan of same with the lid removed.

35 In all of the figures like parts are indicated by the same reference numerals.

40 1 is an outer containing vessel, which is closed by means of a lid 2. The containing vessel 1 is constructed of two parts 3 and 4 of different diameters and an intermediate connecting ledge 5.

45 6 is a drum-shaped receptacle which rests on the ledge 5 and is connected by means of

a depending tubular arm 7, or, if desired, a pair of similar tubular arms, to a cup 8 located below the bottom of the outlet 9 of the apparatus. The cup 8 serves as a support for a block 10 formed of a filtering medium and radio-active material, which may be of the nature already referred to. The block 10 is supported above the bottom of the cup and in such a way that it can be readily removed, and is for this purpose placed in a removable case or holder. This holder may consist, as shown in the drawings, of a coned sleeve 11 provided with suitable diaphragms 12 and 13 and held in place in the top portion of the cup by means of a packing ring 14.

50 15 is a draw-off tap.

The parts of the improved apparatus may be constructed of glass. The drum-shaped receptacle 6, the depending tubular arm 7 and the cup 8 may be made in one piece. This construction is illustrated by Figs. 1 and 2. For the sake of facilitating the construction of the apparatus the above enumerated parts are preferably constructed 55 separate from one another, as illustrated by Figs. 3 and 4. When this latter construction is adopted the major part of the depending tubular arm 17 may be of vulcanite or other like material while the rest of the 60 parts just referred to could be formed of glass. The tubular arm 17 is connected to the cup by a bend pipe 18, and both it and the bend pipe are provided with suitable connecting sockets 19.

65 The apparatus is used in the following manner:—The water or other liquid to be rendered radio-active is poured into the drum-shaped receptacle 6. This water or liquid passes into the depending tubular arm or arms 7 and into the cup 8, and slowly percolating through the block 10 collects in the outer containing vessel 1 from which it is drawn off as required by the tap 15.

70 Having now described my invention what 100 I have invented and desire to secure by Letters Patent in the United States is as follows:

75 1. In a filter, the combination, with an outer vessel provided with a lateral outlet 105 for filtered liquid, of a receptacle, for the liquid to be filtered, supported in the upper part of the said vessel, a tubular arm depending from the said receptacle, a cup carried by the lower end of the said arm and 110

2
arranged below the level of the said outlet, and a removable block of filtering material arranged in the upper part of the said cup.
2. An apparatus for rendering water, mineral water or other liquid radio-active and destroying micro-organisms present in said water or liquid consisting of an outer vessel for containing the radio-active water or liquid, an outlet from said vessel located at a distance above the bottom thereof, a tap controlling said outlet, a lid closing said outer vessel, a receptacle for the water or liquid to be rendered radio-active supported from the upper part of said outer vessel, a

tubular arm depending from the bottom of 15 said receptacle, a cup supported by the lower end of said tubular arm and communicating therewith, and a block containing radio-active material supported by said cup at a level below the outlet from said outer vessel, 20 substantially as described.

In testimony whereof I have signed my name to this specification in the presence of two subscribing witnesses.

EDWARD COUSENS.
